UNITED STATES PATENT OFFICE.

HOUSTON M. CARROLL, SR., OF SAN ANTONIO, TEXAS.

COMPRESSION TRAY.

1,404,271.

Specification of Letters Patent. Patented Jan. 24, 1922.

Application filed December 5, 1921. Serial No. 520,037.

To all whom it may concern:

Be it known that I, HOUSTON M. CARROLL, Sr., a citizen of the United States, residing at San Antonio, in the county of Bexar and State of Texas, have invented a new and useful Compression Tray, of which the following is a specification.

As it is well understood by persons skilled in the art, plaster of Paris, contained in an impression cup is frequently used for taking impressions of the human mouth, in connection with the operation of fashioning artificial teeth. Further, it is well known that the palatine arch is much harder and unyielding than is the alveolar ridge. The result is that when a bite is taken on a mass of plaster of Paris, or the like, in an impression tray, the water is pressed out of the central portion of the mass, by the relatively hard palatine arch, and flows to the edges of the tray, thereby softening the material in which the impression of the alveolar ridge is received. The unsatisfactory results flowing from the foregoing operation will be appreciated readily.

In view of the foregoing, this invention aims, broadly considered, to provide an impression tray, the central portion of which is more yielding than is the peripheral portion thereof, to the end that the palatine arch may not compress the water out of the mixture, thereby softening that portion of the mixture wherein the impression of the alveolar ridge is received.

It is within the province of the disclosure to improve generally and to enhance the utility of devices of that type to which the invention appertains.

In the accompanying drawings:

Figure 1 shows in top plan, a tray constructed in accordance with the invention; Figure 2 is a bottom plan of the tray; Figure 3 is a section on the line 3—3 of Figure 1; Figure 4 is a section on the line 4—4 of Figure 1; and Figure 5 is an enlarged section on the line 5—5 of Figure 1.

In carrying out the invention, there is provided a main member 1 which may be made of metal or any other relatively rigid substance, the main member including a base 2 having an opening 3, the main member being supplied with an upstanding marginal

flange 4. The numeral 5 denotes an auxiliary member, made of metal or some other relatively rigid substance, and having an opening 6, registering approximately at least, with the opening 3 in the main member 1, the auxiliary member being prolonged to form a handle 7 provided with an opening 8 whereby the tray may be suspended when not in use. The auxiliary member 5 corresponds approximately in shape to the base 2 of the main member 1 and is placed therebeneath.

A yieldable and preferably resilient diaphragm 9 is located between the base 2 of the main member 1 and the auxiliary member 5. The diaphragm 9 may be made of rubber or any other suitable material having the physical characteristics above alluded to. Securing elements 10 connect the auxiliary member 5 with the main member 1 and hold the diaphragm 9 in place. The securing elements 10 preferably are removable, to the end that the diaphragm 9 may be renewed, and, if preferred, screws may be used.

When a bite is taken, that portion of the impression material which is compressed by the relatively hard palatine arch will cause the diaphragm 9 to yield, practically none of the water being squeezed out of the impression material to moisten or liquefy that portion of the impression material which receives the impression of the alveolar ridge. The impression material retains its homogeneity, and the clearness of the impression is preserved, especially as regards the alveolar ridge.

What is claimed is:

1. A dental impression tray embodying a marginal portion, and an inner portion which is more yielding than the marginal portion.

2. A dental impression tray comprising a main member having an opening; and a yieldable diaphragm secured to the main member and extended across the opening.

3. A dental impression tray comprising main and auxiliary members having registering openings; and a yieldable diaphragm held between said members and extended across the openings.

4. A dental impression tray comprising main and auxiliary members having regis-

tering openings, the auxiliary member being prolonged to form a handle for the tray; a yieldable diaphragm located between the main and auxiliary members and extended across the openings; and means for connecting the main and auxiliary members releasably, to retain the diaphragm.

In testimony that I claim the foregoing as my own, I have hereto affixed my signature in the presence of two witnesses.

HOUSTON M. CARROLL, SR.
